Patented Feb. 17, 1920.

FIG.1

FIG.2

FIG.3

Inventor:
Frederick Joseph O'Neill
by B. Singer
Attorney

UNITED STATES PATENT OFFICE.

FREDERICK JOSEPH O'NEILL, OF DUNEDIN, NEW ZEALAND.

ELECTRIC-LAMP LOCK.

1,331,355.

Specification of Letters Patent. Patented Feb. 17, 1920.

Application filed August 12, 1918. Serial No. 249,517.

To all whom it may concern:

Be it known that I, FREDERICK JOSEPH O'NEILL, a subject of King George V of Great Britain, residing at 40 Dowling street, 5 Dunedin, in the Dominion of New Zealand, have invented certain new and useful Improvements in Electric-Lamp Locks, of which the following is a specification.

The main object of this invention is to 10 prevent the unlawful removal of an electric lamp from a bayonet joint fitting.

Other objects accomplished by the means I adopt to prevent the unlawful removal of the electric lamp, are; prevents arcing between the spring contacts in the socket member of the bayonet fitting and the contacts on the face of the spigot end of the bayonet joint member; prevents end play in the bayonet joint of an electric lamp, considerably 15 reduces vibration and oscillation of the lamp in its socket, and thus generally increases the efficiency of the lamp.

In a loose bayonet fitting the spring contacts do not prevent arcing; frequently the 20 lamp oscillating in one direction or another disengages one or another of the spring contacts in the bayonet socket and causes arcing, creating heat in the fitting; this effects the temper of the spring contacts, and considerably 25 reduces the efficiency of the lamp.

In the drawings accompanying this specification,

Figure 1 is a perspective view of the lamp lock.

Fig. 2 is a perspective view of an electric lamp showing the lamp lock loosely applied to the bayonet joint connection as it would appear before being clenched thereon.

Fig. 3 is a view showing the lamp lock 40 applied to the bayonet joint connection, and clenched thereon.

I take a strip 1 of suitable material, preferably metal, approximately $3\frac{3}{4}$ " long, by $\frac{3}{16}$ " or one quarter of an inch wide, and 45 form a circle as in Fig. 1, of approximately one inch in diameter, to fit the spigot end 2 of the bayonet fitting on the lamp 3, one end of the strip 1 is crimped as at 1^A, while the other end is slightly bent as at 1^B, to adapt 50 it to engage with the crimp 1^A.

It will be observed that when the lamp 3 is connected up, that is, the spigot end 2 of the bayonet joint which is on the lamp 3 en-

gages with the socket member 4 of the bayonet joint, a groove 5 is created between the 55 edge 4^A of the socket member 4 of the said joint and the enlarged portion 2^A of the spigot member 2 of the said joint, the space which creates the groove 5 being necessary for the engagement and disengagement of 60 the lamp with the electric light fitting.

I apply the strip 1 having the crimp end 1^A and the bent end 1^B to the groove 5 in the bayonet joint, engage the bent end 1^B of the strip 1 in the crimp 1^C, as in Fig. 2, 65 and with a pair of pliers or any suitable tool 70 clenched the bent end 1^B within the crimp end 1^A and bend them over approximately flush with the socket member 4 of the joint, as in Fig. 3.

The strip 1 closes up the groove 5 and 75 prevents end play of the lamp in the socket 80 against the influence of the spring contacts in the socket member 4 of the bayonet joint, thus preventing the removal of the lamp, 75 also considerably reduces oscillation and vibration of the lamp.

What I claim as new and desire to secure by Letters Patent is:—

1. An electric lamp lock, comprising in 80 combination with a lamp having its base formed as a shouldered spigot member and a socket member connected to said spigot by a bayonet joint, a metal strip applied to the space formed by the spigot and socket members in connected position, said strip engaging the inner edge of said socket member and shoulder of said spigot member. 85

2. An electric lamp lock, comprising in 90 combination with a lamp having its base formed as a shouldered spigot member and a socket member connected to said spigot member by a bayonet joint, a metal strip applied to the space formed between the shoulder of said spigot and the end of the 95 socket member when connected, said metal strip having its ends fashioned in a manner to permit said ends to be clenched together after the said strip of metal has been applied. 100

3. An electric lamp lock, comprising in 105 combination with a lamp having its base formed as a shouldered spigot member and a socket member connected to said spigot member by a bayonet joint, a metal strip engaging the inner edge of said socket member

and the shoulder of said spigot, the strip having one end crimped and the other end adapted to engage the said crimp, and when engaged both ends are adapted to be bent over and lie approximately flush with the outside surface of the bayonet joint.

5 In testimony whereof I have hereunto

set my hand in presence of two subscribing witnesses.

FREDERICK JOSEPH O'NEILL.
